UNITED STATES PATENT OFFICE.

ARTHUR W. RICHES, OF LOS ANGELES, CALIFORNIA.

PARACHUTE.

1,186,230.

Specification of Letters Patent.

Patented June 6, 1916.

Application filed January 19, 1914. Serial No. 818,010.

To all whom it may concern:

Be it known that I, ARTHUR W. RICHES, a citizen of the United States, residing at Los Angeles, in the county of Los Angeles and State of California, have invented new and useful Improvements in Parachutes, of which the following is a specification.

This invention relates to improvements in parachutes relevant to the art in general, but 10 more especially to improvements in aeronautical life saving devices, which are applicable for safely descending from monoplanes and all other types of aerial craft, wherein it is desired to descend to the earth 15 from any altitude.

An object of the invention is primarily the provision of an improved aeronautical descending device of the above general relation, comprising a plurality of parachutes 20 so arranged and disposed in their relation to each other that when projected into the air they act in unison in the support of human cargo.

Another object of the invention is the provision of an improved parachute of the character stated that is placed ready for use in a suitable receptacle supplied in connection therewith, there also being operating-means for the release of projecting-means, for projecting one of the parachutes into the air and when the same is inflated it pulls the other parachutes without said receptacle.

Another object of the invention is the provision of an improved aeronautical life saving device of the above character, which embodies a separably connected belt which is worn by the aeronaut and when in flight is attached to the supporting cables from said parachute, so that in alighting the belt may 40 be very easily unbuckled from said cable and the aeronaut then runs clear of the collapsing parachutes.

A further object of the invention is the provision of a parachute possessed of the 45 above advantages that is superior in point of relative simplicity and inexpensiveness of construction, positiveness in operation, and in point of efficiency and general serviceability.

With the above and other objects in view the invention further consists in the new

and novel provision, formation, construction, combination, organization and relative arrangement of parts, members and features, all as hereinafter fully described and 55 shown in the drawings, and finally pointed out in the claims annexed hereto.

In the drawings:—Figure 1 is a top plan view of the invention as the same appears when inflated and in use; Fig. 2 is a central 60 vertical cross-sectional view of one of the sections of the parachute; Fig. 3 is an enlarged detail of the spider-guide-collars supplied and shown in the other views; Fig. 4 is a detail view to an enlarged scale of the 65 anchor-clamp or bracket supplied in the invention; Fig. 5 is a central sectional view in detail of the same part shown in Fig. 4; said view being taken at right angles thereto; Fig. 6 is an exterior side elevation of the 70 upper portion of the preferred form of the invention comprising a plurality of parachutes each acting independent of the other. Fig. 7 is an enlarged view in detail of the snaps and interconnecting means for the life or 75 supporting belt; Fig. 8 is a view of the spider-guide-collars and the air exits or vents in the top of each of the two lower parachute sections; Fig. 9 is a central vertical sectional view of the parachute receptacle with its various adjuncts as the same is placed within the body portion of a monoplane, in the vicinity of the operator's seat. Fig. 10 is a top plan view of the same parts shown in Fig. 9 and taken on the line 80 X¹⁰—X¹⁰ of Fig. 9; Fig. 11 is a top plan view of the supporting-belt; Fig. 12 is a front elevation of said belt; and Fig. 13 is a view showing the shoulder pad on an 85 aviator's jacket. 90

Like characters of reference designate like parts and combinations of parts throughout the several views of the drawings.

Referring to the drawings the letter A denotes a parachute constructed of suitable material capable of being crushed into a relatively small space, B designates a similar parachute of larger proportions than the 95 parachute A and C is a like parachute of greater size than B; said parachutes being 100 arranged one above the other and increasing in size one under the other. Said parachutes

A, B and C are provided at their tops with air exits or vents *a*, *b* and *c* respectively; there being spider-guide-collars *b'* and *c'* in said air exits *b* and *c* and a continuous supporting-cable D extending from said upper parachute A downwardly through B and C and through said collars *b'* and *c'*.

E denotes the guy cables of the parachute A and to which the supporting-cable D is attached and F and F' are the guys of the parachutes B and C respectively; said guys F and F' having the spider-supporting brackets G in connection therewith.

The cable D is supplied with suitable anchor-brackets *d* and *e* for contacting with said brackets G or with the guide-collars *b'* and *c'*.

The aeroplane H is supplied with the receptacle I for containing the parachutes B and C in a crushed or compact condition and J is the projecting-means for projecting the upper parachute A into the air, K denotes the means for releasing said projecting-means J, the same being in the vicinity 25 of the customary aviator's seat L from where it is easily reached.

M designates a belt having a crotch-strap *m* and suitable snap and ring safety connecting means P to a portion of which the supporting-cable D is detachably fastened.

Referring with particularity to the drawings the parachute proper comprises the individual chutes or sections A, B and C, arranged one above the other substantially as shown, the section A being the top or uppermost, the section B being directly thereunder and of relatively larger proportions and the section C being directly under the other sections A and B; said section C being of relatively larger proportions than the section B. The section A specifically comprises an umbrella shaped parachute which is preferably constructed of silk fabric (which may be oiled if necessary) capable of being crushed into small space when not in use and which may be suitably reinforced or strengthened by means of cross-sewing or stitching after the methods now employed in the production of parachutes. Located centrally of the section A is an opening or air exit —*a*— for equilibrating the section when in use as hereinafter described. At the lower edge of said section, fastened as at 12 and extending downwardly therefrom are 55 the guy cables of any desired material which converge and are each connected with the other as at 13, at which point the supporting cable D is fastened thereto and from which the latter depends centrally thereof.

At a predetermined point below and centrally of said section A are the sections B and C, said section B being proportionally increased to approximately twice the size of the section A and being constructed of sim-

ilar material; there being a similar air vent *b* in the top of the said section B in which is suitably fastened as at 14 the spider-collar *b'* constructed as shown in Fig. 8 having a guiding collar 15 with a hole 15^a therein through which the supporting cable D is moved as will be hereinafter more fully described. At the lower edge of said section B, fastened as at 16 and converging downwardly therefrom, are the like guy cables F, which in turn are fastened as at 17 to the spider-supporting-bracket G, the latter having a collar 18 in its center in the opening 19 of which the cable D is moved in the operation of the invention. At a predetermined distance below said section B is the section C which is increased in proportion to approximate twice the size of the section B, the same being constructed of like material and having a like spider-guide-collar *c'* fastened as at 20 in the opening 21; said collar *c'* being identical with the collar *b'* with the exception that it is proportionally larger than the collar *b'* as the opening or air vent *c* is proportionally larger than the vent *b*. Said section C has like guy cables F' fastened thereto as at 22 extending downwardly therefrom and converging centrally thereof at which point a like spider-supporting-bracket G' is suspended there being a like collar 18 having therein a like opening 19 for the cable D. Fastened to the cable D as at 23 are the anchor-brackets *d* and *e* having their contacting edges 24 opposed to each other, the brackets *d* under certain conditions of use coming to rest on the supporting-brackets G and G' and the brackets *e* contacting with the collars *b'* and *c'* as hereinafter more fully described.

The aeroplane H herein shown is of the monoplane type embodying the body portion 105 25 and is supplied with the customary seat L for the aviator, an approximate showing of the structure being had in Figs. 9 and 10 of the drawings. The body 25 is supplied with the lateral supports 26 for supporting 110 the receptacle preferably within said body 25. At the front of the receptacle I and at or adjacent to the front of said body 25 is located said aviator's seat L, which may be of the rocking or stationary models and at 115 the back of said seat is the transverse wall 27 for the combined purpose of supplying a back for said seat, closing in the receptacle, and providing a guide for removing the aviator out of said aeroplane as will be hereinafter fully described.

The receptacle I comprises the wall 28 forming the compartment 29, the bottom of said receptacle being supported by said lateral supports 26 within the side walls 30 of the aeroplane body 25. A lid or covering 31 is provided on said receptacle, and is fastened thereto as by the hinge 32, there being

an orifice 33 in the covering 31 for the cable D. At the rear of said receptacle the projecting-means J is provided, the same comprising a suitable cylinder 34 the top of which 5 may extend above the horizontal plane of the top of said receptacle and within which the spring 35 is coiled below the piston 36 around the piston-rod 37 the latter extending through the bottom 38 of said cylinder 34 and having a knob 39 on its lower end within reach of the opening 40 in the body 25 of the aeroplane H, so that said knob may be moved to set the projecting means J. The means K for releasing said projecting 10 means J comprises a handle or lever 41 affixed to or adjacent the seat L or located at one side of said seat and on the side wall 30 of said aeroplane body 25 and within easy reach of the aviator; said handle or lever 41 being movably mounted as at 42 so that the same operates the cord or cable 43 extending therefrom, over the rollers 44 and through the holes 45 in said transverse wall 27 and through the holes 46 in said lateral 15 supports 26 to the rod 47 where said cord is fastened as at 48 to said rod. The rod 47 extends through the hole 46^a in one of said lateral supports 26 and is provided with a spring 49 fastened thereon as at 50 so that 20 in moving said rod to slide the end 51 thereof in the bottom 38 of said cylinder 34 and withdraw the same from hole 52 in said piston-rod 37, the lever 41 is moved to overcome the pressure of said spring 49.

25 The belt M comprises the main portion 53 fitting around the waist of the aviator and his passengers and the crotch portion m extending from the back of said belt to the front thereof and which fits in the crotch 30 between the lower limbs of the aviator or his passengers. Said belt is provided with suitable snap and ring interconnecting means P which comprises a three-way bracket 54 having a ring 55 projecting upwardly therefrom, a ring 56 extending downwardly therefrom for the crotch part m and a ring 57 projecting laterally therefrom. The crotch strap m, the belt M and the end 35 of the cable D are each provided with an ordinary spring snap 58 such as are supplied on harness which comprises a thumb-latch 59 normally held in closed position by the spring 60, the snaps 58 being fastened to said belt M, to the crotch-strap m and to the end of said cable D as by the rivets 61.

40 *Modus operandi:* The various parts are assembled substantially as just described with the upper or smaller parachute A folded or crushed in the cylinder 34 and so arranged that the cable D extends from the bottom thereof which is also the top of the piston 36, to and through the relatively long slot 61^a which ranges in said cylinder to the top thereof. That portion of the cable D 45 intermediate the parachute sections A and B 65 ranges within said compartment 29 at the upper part of which the parachute B is placed in compact folded position and that part of the cable intermediate the parachute sections B and C is coiled between said sections in said compartment 29 of said receptacle I; the section C being compactly folded at the bottom of said compartment with that portion of the cable D extending below said lower section C being turned upwardly at 70 the side of said compartment. The cable D then ranges along the top of said receptacle under the hinged covering 31, through the orifice 33 and thence over the top of said covering 31 to the aviator. It is found desirable to supply a shoulder pad 63 having a suitable hook 62 as shown in Fig. 13 fastened on the coat or jacket 64 usually worn by the aviator so that said cable D may extend downwardly over the front of 85 said jacket 64 to the belt M where the snap 58 is employed to fasten said cable in the ring 55 so that the cable does not interfere with the aviator in the manipulation of the necessary mechanisms for controlling the 90 aeroplane while in flight. When the aviator has for any reason lost control of the aeroplane and desires to abandon the same in its downward plunge he manipulates the lever 41 to project the parachute section A into 95 the air which spreads or inflates instantly and then pulls the covering open and the parachute section B without the receptacle; said section B as it inflates pulling the section C without said receptacle. When all of 100 said sections A, B and C are inflated the sustentation capacity thereof very readily raises the aviator off the seat and upwardly out of the aeroplane as the same is dropping.

105 The parachute sections A, B and C, one arranged below the other and each increasing in relative proportions, may be used without the receptacle herein shown and described and without the projecting and releasing means herein shown in descending 110 from any altitude it simply being necessary that a belt substantially as shown be affixed to the supporting-cable D.

115 When the projecting means J, which may be in the form of an explosive in substitution for the spring actuated mechanism herein shown and described, is used to project the uppermost or smaller parachute section A into the air and as the same is inflated the anchor-brackets are brought into 120 contact with the guide collars b' and c'; said guide-collars thereby raising the parachute sections B and C in operative working position for inflation in the air and after such inflation the guy-cables F and F' thereby 125 raise the supporting brackets G and G' upwardly on said cable D until they are brought into contact with anchor-brackets d

so that any weight on said cable is thereby supported by said parachute sections B and C and to a lesser degree by said section A.

The air vents *a*, *b* and *c* are so constructed with proper regard to the general proportions of the sections A, B and C that the sustaining capacity of the device when inflated is very great and a more efficient device is thereby provided.

10 The invention contemplates the provision of any plurality of planes or parachutes of any like size or any series of various sized parachutes of relatively increasing or decreasing proportions one above the other.

15 It is obvious that the invention may be applied to various modifications in the more extensive utilization of the same, therefore, I do not desire to be understood as limiting myself to the specific provision, formation, 20 construction, combination, organization and relative arrangement of parts, members and features, as herein shown and described but reserve the right to vary the same within the scope of the invention and the terms of the 25 following claims.

Having thus fully described my invention, what I claim and desire to secure by Letters Patent, is:

1. An aeronautical life saving device comprising a plurality of parachute sections, one above the other and increasing in relative proportions one below the other; air vents for increasing the sustentation and the stabilizing capacity of each of said sections; guide collars in the air vents of the lower parachute sections; a cable guyed to and extending from the upper section and through said guide collars in the vents in the lower sections; a detachable belt on said cable; a receptacle for containing said sections in folded compact form; and projecting means in said receptacle for projecting one of said sections for inflation.

2. An aeronautical life saving device comprising a plurality of parachute sections, one above the other and increasing in relative proportions one below the other; air vents for increasing the sustentation and the stabilizing capacity of each of said sections; a cable guyed to and extending from the upper section and operatively through said vents in the lower sections; a detachable belt on said cable; a receptacle for containing said sections and the major portion 55 of said cable in folded compact form; and projecting means in said receptacle for projecting the upper of said sections for inflation.

3. An aeronautical life saving device comprising a plurality of parachute sections arranged one above the other; air vents in each of said sections; guide collars in the vents of the lower of said parachute sections; a cable fastened to the upper and

extending through said guide collars in the 65 vents of the other of said sections; a belt for detachable attachment to said cable; a receptacle for containing said sections and having means therein for projecting one of said sections; and means for releasing 70 said projecting means to inflate the sections and support an aviator by said belt.

4. An aeronautical life saving device comprising a plurality of parachute sections arranged one above the other; air vents in 75 each of said sections; guide collars in the vents of the lower of said sections; a cable fastened to the upper and extending through the guide collars in the other of said sections; a belt for detachable attachment to 80 said cable; a receptacle for containing said sections in compact folded condition and having means therein for projecting one of said sections; and means for releasing said projecting means to inflate the sections and 85 support an aviator by said belt.

5. An aeronautical life saving device comprising a plurality of parachute sections ranging one above the other and each being of relatively smaller proportions; air vents 90 in each of said sections; guide collars in each of the lower sections; a cable suitably fastened to the guy cables of the upper section and operatively extending through the other of the sections; a supporting bracket 95 suspended below each of said lower sections; and anchor brackets on said cable for engaging the supporting brackets and the guide collars, substantially as described.

6. An aeronautical life saving device comprising a plurality of parachute sections ranging one below the other and each being of relatively larger proportions; air vents in each of said sections and having guide-collars therein; guy-cables for suspending 105 a supporting-bracket below each of said lower sections; a cable guyed to said upper section and extending through said lower sections; anchor-brackets on said cable for contact with said guide-collars and with 110 said supporting-brackets; a belt detachably affixed to said cable; a receptacle for containing said sections in compact form; projecting-means in said receptacle; and means under control of the aviator or operator for 115 releasing said projecting means.

7. An aeronautical life saving device comprising a plurality of parachute sections ranging one below the other and each being of relatively larger proportions; air vents 120 in each of said sections and having guide-collars therein; guy-cables for suspending a supporting-bracket below each of said lower sections; a cable guyed to said upper section and extending through said guide 125 collars in said lower sections; anchor-brackets on said cable for contact with said guide-collars and with said supporting-

brackets; a belt detachably affixed to said cable; a receptacle for containing said sections in compact form; projecting-means in said receptacle for projecting said upper section; and means under control of the aviator or operator for releasing said projecting means.

In testimony whereof, I have signed my name to this specification in the presence of the two subscribing witnesses.

ARTHUR W. RICHES.
